DESIGN FOR A SWITCH COVER PLATE OR SIMILAR DEVICE

Rufus G. Fordyce, Chicago, Ill.

Application March 19, 1938, Serial No. 75,969

Term of patent 14 years

To all whom it may concern:

Be it known that I, Rufus G. Fordyce, a citizen of the United States of America and residing at 2223 Farwell Avenue, Chicago, in the county of Cook and State of Illinois, have invented a new, original, and ornamental Design for a Switch Cover Plate or Similar Device, of which the following is a specification, reference being had to the accompanying drawing, forming a part thereof in which:

Fig. 1 is a front view of a switch cover plate showing my new design.

Fig. 2 is a bottom edge view of Fig. 1.

What I claim is:

The ornamental design for a switch cover plate or similar device substantially as shown.

RUFUS G. FORDYCE.
